(57) CLAIM

The ornamental design for a purse, as shown and described.

DESCRIPTION

FIG. 1 is a front perspective view of a purse showing our new design;

FIG. 2 is a front view thereof;

FIG. 3 is a top view thereof;

FIG. 4 is a bottom view thereof; and,

FIG. 5 thereof is a right side view thereof, the left side being a substantial mirror image thereof.

The strap is shown broken away in the views to indicate indeterminate length.

The broken line showing of a hinge, on the side straps, in FIGS. 1, 2, 4, and 5, and the rear portion, in FIGS. 3–5, is for illustrative purposes only and forms no part of the claimed design.
